(57) **CLAIM**

The ornamental design for a Christmas tree, as shown and described.

DESCRIPTION

FIG. 1 is a perspective view of a Christmas tree showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The star, ornaments and small circles on the edges of the branches are shown in broken lines and do not form part of the claimed design.
